UNITED STATES PATENT OFFICE.

HARVEY J. SALLEE, OF WHITEHOUSE, CALIFORNIA.

INTERNAL-COMBUSTION ENGINE.

1,380,742.

Specification of Letters Patent. Patented June 7, 1921.

Application filed August 6, 1917. Serial No. 184,647.

To all whom it may concern:

Be it known that I, HARVEY J. SALLEE, a citizen of the United States, and a resident of Whitehouse, Shasta county, State of California, have invented a certain new and useful Improvement in Internal-Combustion Engines, of which the following is a specification.

The invention relates to internal combustion engines and particularly to a rotary distributor valve for conveying the explosive mixture and the products of combustion.

An object of the invention is to provide means for cooling the valve.

Another object of the invention is to provide a valve which may be cooled with either air or water or both.

A further object of the invention is to provide means for the passage of a cooling fluid between the intake gas passage and the exhaust gas passage.

A further object of the invention is to provide means for lubricating the entire surface of the distributor valve.

The invention possesses other advantageous features, some of which, with the foregoing, will be set forth at length in the following description where I shall outline in full that form of the invention which I have selected for illustration in the drawings accompanying and forming part of the present specification. In said drawings I have shown several embodiments of my invention but it is to be understood that I do not limit myself to such forms, since the invention, as expressed in the claims, may be embodied in a plurality of forms.

Referring to said drawings:

Figure 1 is a vertical longitudinal section of a multi-cylinder internal combustion engine showing one form of rotary distributor valve of my invention.

Fig. 2 is a longitudinal section of the distributor valve shown in Fig. 1.

Fig. 3 is a cross section of the engine head taken on the line 3—3, Fig. 1.

Fig. 4 is a similar cross section taken on the line 4—4, Fig. 1.

Fig. 5 is a similar cross section taken on the line 5—5, Fig. 1.

Fig. 6 is a similar cross section taken on the line 6—6, Fig. 1.

Fig. 7 is a longitudinal section of a modified form of distributor valve in which two

separate cooling fluids may be used, part of the valve being broken away to reduce the size of the figure.

Figs. 8 and 9 are similar views of other modified forms of valve.

Fig. 10 is a cross section of the valve taken on the line 10—10, Fig. 9.

My invention relates to a rotary distributor valve for multicylinder engines, which serves as a conduit for the explosive mixture and the exhaust gases and which functions by its rotation to open the passages within the valve to the cylinders at the proper time. In accordance with my invention, I provide a rotary distributor valve in which a cooling fluid flows between the inlet and exhaust conduits which lowers the temperature of the exhaust conduit and checks or retards the transfer of heat to the intake conduit. I also provide means for properly lubricating the entire surface of the valve, and this in combination with the cooling effect produces an efficient operating structure.

The rotary distributor valve of my invention is particularly adapted for use in multicylinder engines and is preferably disposed in a cylindrical seat 12 formed directly over the cylinders 13, the wall between each cylinder and the valve seat 12 being provided with a port 14 for the passage of the explosive mixture and the gases of combustion. The distributor valve 15 is rotated in time with the crank shaft of the engine through the medium of the gear 16 secured thereto and the chain 17 engaging said gear and a gear of the proper size on the crank shaft.

The distributor valve is formed of a plurality of concentric tubes or conduits through which the various gaseous mixtures pass and the tubes are provided with ports opening on the face of the valve and in position to register at the proper time with the ports 14. The gaseous mixture conveying tubes are spaced apart radially forming passages between them for a cooling fluid or fluids. The distributor valve shown in Figs. 2, 3, 4, 5 and 6 comprises an outer or bearing tube 18 which forms the outer wall of the explosive mixture passage into which the explosive mixture is introduced from the conduit 20 through the rows of circumferential ports 19 disposed adjacent the ends of the tube 18. This tube is provided with a plurality of properly disposed ports 21 through which

the explosive mixture passes into the cylinders.

Arranged within and concentric with respect to the outer tube is an inner tube 22 for the exhaust gases, and at each cylinder, the tube 22 is provided with a port 23 extending to the surface of the valve and provided on the sides with walls 24 to separate it from the other passages within the valve. Arranged intermediate the tubes 18 and 22 are tubes 25 and 26 which form passages for the cooling fluid, the tube 25 forming the inner wall of the explosive mixture passage. This tube is flanged at its ends and is joined to the outer tube at the sides of the apertures 19 adjacent the ends of the tube, thereby separating the explosive mixture passage from the cooling fluid passages. The tubes 25 and 26 are also flanged and secured to the outer and inner tubes adjacent the exhaust ports 23 so that chambers 27 for the cooling fluid are formed immediately behind the walls 24, and this keeps the walls 24 cool and reduces the temperature of the exhaust gases before they enter the tube 22. The tubes 25 and 26 are open on their ends and the tube 18 is open at its forward end to permit the free flow of the cooling fluid therethrough. The cooling fluid may be air or water, and in the construction shown in Fig. 2, I prefer to use air which enters the valve through the open forward end of the tube 18. When the engine is used on motor vehicles, the speed of the vehicle forces air into the tube and this action is increased by a fan 31 arranged in the forward end of the tube. The air, after passing through the tube, discharges through the apertures 29 in the outer tube 18 which register with apertures 28 formed in the seat 12. By forming two separate longitudinal passages for the cooling fluid, the hot fluid produced by contact with the exhaust tube 22 is prevented from coming into direct contact with the tube 25 and thereby the tube 25 is kept cooler than if only one fluid passage were employed.

Means are provided for effectively lubricating the bearing surface of the valve. Extending down through the head 32 of the engine, which is formed as a water jacket for the bearing cylinder 12 are a plurality of oil conduits 33 connected to the distributing pipe 34. The outer surface of the tube 18 is provided in line with each conduit 33 with a circumferential oil groove 35 and the excess oil is drained off through the tubes 36 communicating with the valve seat at the bottom and opening into the grooves. The grooves 35 are preferably arranged between the cylinders. In order to insure the lubrication of the valve and seat between the grooves, I have provided a bridge 37 in each inlet port 21, the face of the bridge 37 being flush with the face of the tube 18.

Formed in the bridge are grooves 38 which communicate with the oil grooves 35 on opposite sides of the port and the bridge and grooves are inclined backwardly with relation to the direction of rotation of the valve, so that the rotation of the valve causes the oil to be forced along the bridge grooves to the center of the bridge, thereby lubricating the entire valve surface between the circumferential grooves. The two arms of the bridge are inclined backwardly in respect to the direction of rotation of the valve, to the center of the port and are there joined by a circumferentially disposed bridge arm 39 forming a Y-shaped bridge over the port. The arm 39 is provided with a groove 41 which joins the grooves 38 and the groove 41 opens on the sides of the arm 39 and into the intake manifold, so that the oil in the groove is subjected at all times to the vacuum existing in the intake manifold. This causes a positive flow of the oil in the groove and prevents the oil from carbonizing and collecting in the grooves and choking them. The impeller force of the inclined grooves in combination with the continual pull of the vacuum causes the oil to flow freely through the grooves.

The construction shown in Fig. 7 is designed for use with two cooling fluids, such as air and water. The tube 25 is flanged on its ends and joined to the outer tube 18 as in the prior construction. The tube 26 is also flanged on its ends and is joined to the outer tube 18 at points beyond the points of attachment of the tube 25, thereby forming two separate cooling fluid passages. Water is admitted to the outer passage through the apertures 42 in the outer tube, passes longitudinally through the valve and discharges through the apertures 43 at the other end. Stuffing boxes 44 and 45 arranged adjacent the apertures 42 and 43 prevent water leakage at these points. Air is admitted through the forward end of the outer tube and driven by the fan 31 passes longitudinally through the passage immediately surrounding the exhaust manifold 22 and is discharged through the apertures 46 at the other end of the valve.

In the structure shown in Fig. 8, only one tube 25 is arranged between the outer tube 18 and the exhaust manifold 22 and air or water may be flowed through the passage formed between the tubes 22 and 25. This cooling fluid is introduced into and moved through the passage in the same manner as previously set forth.

In the construction shown in Figs. 9 and 10, only one cooling fluid is used, which may be air or water, and the fluid is introduced into and discharges from the valve at the same end, passing down along the length of the valve and back before it discharges. The cool fluid is preferably passed first in

contact with the wall of the inlet manifold, so that the outer surface of the valve is kept cool, and back in contact with the hotter wall of the exhaust manifold. The passage between the tubes 25 and 26 is closed at one end and open at the other and the cooling fluid is introduced through the pipe 48 into the closed end of the passage, passes down for the length of the passage and then reverses and passes back through the passage between the tubes 22 and 26 and discharges through the pipe 49, the fan 31 in this instance being arranged to discharge the cooling fluid. The joints between the tubes 25 and 26 and the stationary structure of the engine head are closed by suitable stuffing boxes 51 and 52 to prevent leakage. In this construction, the wall 25 is semi-circular in form at intervals and is provided at intervals with flanges 53 secured to the outer tube 18, thereby opening the passages between the tubes 25 and 26 to the outer tube 18 and bringing the cooling fluid in direct contact with the outer tube.

25 The chambers so formed behind the outer tube 18 are arranged so that they register with the cylinder ports 14 as the valve rotates, so that the areas of the outer tube which are subjected to the hot gases of explosion are water jacketed on their rear surface, so that they are kept cool.

I claim:

1. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, bridges over said ports, grooves in said bridges and means for conducting lubricating oil to said grooves.

2. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, circumferential lubricating oil grooves on said valve, a bridge extending over said port and a groove in said bridge communicating with said circumferential grooves.

3. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, circumferential lubricating grooves on said valve, a bridge across said port inclined backwardly with relation to the direction of rotation of the valve, and a groove in said bridge communicating with said circumferential grooves.

4. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, circumferential lubricating grooves on said valve, and a bridge across said port provided with a groove opening at one end in a circumferential groove and at the other end into said port.

5. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, circumferential lubricating grooves on said valve and a Y-shaped bridge across said port, having a groove communicating with said circumferential grooves.

6. In an internal combustion engine, a plurality of cylinders, a cylindrical valve seat arranged adjacent said cylinders, passages connecting the cylinders with said seat, a rotary distributer valve bearing in said seat and provided with ports adapted to register with said passages, an inclined bridge extending across said port, a groove in said bridge opening into said port and means for supplying lubricating oil to said groove.

7. In a rotary distributer valve for multi-cylinder internal combustion engines, an inner tube forming an exhaust gas passage, an outer tube, a third tube arranged within the outer tube and forming therewith an explosive mixture passage, and a fourth tube arranged between the inner tube and the third tube and spaced from both of said tubes and forming two passages between the exhaust gas passage and the explosive mixture passage, and means for passing cooling fluid through said two intermediate passages.

8. In a rotary distributer valve for multi-cylinder internal combustion engines, an inner tube forming an exhaust gas passage, an outer tube, a third tube arranged within the outer tube and forming therewith an explosive mixture passage, and a fourth tube arranged between the inner tube and the third tube and spaced from both of said tubes and forming two passages between the exhaust gas passage and the explosive mixture passage, means for passing air through one of said intermediate passages and means for passing water through the other intermediate passage.

9. In an internal combustion engine, a rotary distributer valve inclosing an intake manifold, a port in said valve communicating with said manifold, a bridge across said

port, a groove in said bridge opening into said manifold and means for supplying lubricating oil to said groove.

10. In an internal combustion engine, a
5 rotary distributor valve having a port opening on the face thereof, a series of circumferential oil grooves in said valve spaced longitudinally thereof, oil grooves in said valve disposed longitudinally thereof and connecting said circumferential grooves, means for introducing oil into said circumferential grooves and a groove connecting each longitudinal groove with said port.
11. In an internal combustion engine, a
15 plurality of cylinders, a casing forming a valve seat arranged adjacent said cylinders, ports connecting the cylinders with said seat, a rotary valve arranged in said seat and provided with ports adapted to register
20 with said cylinder ports, a circumferential groove on said valve on each side of said port, a transverse groove connecting the circumferential grooves, a groove connecting

the transverse groove with one of said valve ports and means for conducting lubricating oil to said circumferential grooves. 25

12. In an internal combustion engine, a plurality of cylinders, a casing forming a valve seat arranged adjacent said cylinders, ports connecting the cylinders with said seat, a rotary valve arranged in said seat and provided with ports adapted to register with said cylinder ports, a pair of circumferential grooves for each of said valve ports, a transverse groove connecting the circumferential grooves of each pair, a groove connecting each transverse groove with the relative port, and means for conducting lubricating oil to said circumferential grooves. 30 35

In testimony whereof I have hereunto set my hand at San Francisco, California, this 12th day of July, 1917.

HARVEY J. SALLEE.
